UNITED STATES PATENT OFFICE.

VENE L. FIDLER, OF BALTIMORE, MARYLAND.

PAPER-CUTTING MACHINE.

1,365,475.

Specification of Letters Patent. Patented Jan. 11, 1921.

Application filed December 13, 1919. Serial No. 344,548.

To all whom it may concern:

Be it known that I, VENE L. FIDLER, a citizen of the United States of America, residing in the city of Baltimore, State of Maryland, have invented certain new and useful Improvements in Paper-Cutting Machines, of which the following is a specification.

Photographic prints, as made, necessarily have a wide margin on four sides, which must be trimmed before the photograph presents a finished appearance. The expense incident to trimming photographic prints in this way is due to the failure of the paper cutting machines in use to do this work efficiently. The apparatus offered for this purpose, having but one shearing blade, will trim one side only at each operation, and the manually operated cutting or trimming machines that have been in use in the past will cut but a few thicknesses or sheets at one time. The single blade cutting machines cause the paper to buckle and gather toward the blades, when being used to cut more than two or three thicknesses, giving the paper or print, when cut, an uneven edge or margin. In photographic work, it is important that the trimmed edges be parallel. The single blade cutters will not give the desired result.

The object of this invention is to provide a machine that will overcome these inefficiencies, that is, one which will handle a large number of prints or sheets at each operation and cut the edges parallel and at right angles without difficulty so that no skill in operation is necessary. The structure also has the advantages that it is cheap, simple and durable and can be maintained without expense.

In its preferred form the paper cutter consists of two cutting or shearing blades, held in parallel relation and adapted to be adjusted in parallel relation toward and from each other; a cutting-board with graduations to determine the positions of the cutting blades; adjustable stops or guides carried by the cutting board, and means for operating the blades together with a shearing motion in relation to and in co-operation with the cutting-board.

In the accompanying drawing I have illus-

trated a paper cutter embodying the features of my invention in the preferred form.

In the drawings—

Figure 1 is a side elevation of the complete paper cutting machine, showing the blades in full lines in inoperative position and in fine dotted lines in operative position.

Fig. 2 is a plan view of the complete device.

Fig. 3 is an end elevation illustrating several thicknesses of paper or photographic prints ready to be cut or trimmed.

Referring to the drawings by numerals, I have illustrated a photographic print cutting device or paper cutting machine which consists of frame members 1 and 2 supported or held in rigid relation each with the other by stiffening or end frame bars, 3 and 4. The frame members 1 and 2, carry shafts 6 and 7, which are held in place by any suitable means, as cotter pins, 8 and 9 respectively. Pivotaly mounted on each of these shafts, 6 and 7, are two pairs of extension or swinging arms, 10 and 11 respectively which move in an arc of about 90 degrees about the respective shafts, 6 and 7, as shown in full and in dotted lines in Fig. 1 of the drawing. These arms each have bearings at 12 and 13 by which they engage shafts 6 and 7, the shafts each in turn have bearings, 14 and 15 respectively in the frame members, 1 and 2. As shown in the drawing, particular reference being made to Fig. 2, it will be seen that the frame members, 1 and 2, are each slotted at 16 and 17 respectively as a guide for the arms, 10 and 11. At the uppermost ends of these swinging arms, 10 and 11, are bearings, 18 and 19, for the blade, supporting shafts or rods, 20 and 21, which may be held, as shown, in their proper positions by cotter pins, 9. The shafts, 20 and 21, act as supports for the blade carrying members 22 and 23, which are adjustable on and in sliding relation to the shafts 20 and 21, both blade carrying members or arms having bearings 24 and 25, which are adjustable along shafts, 20 and 21, permitting the blades, knives or shearing members, 26 and 27, to be adjusted in parallel relation to any position within the limits of the length of the shafts, 20 and 21.

The blades may be held in place or attached to the blade carrying members by means of screws or rivets, 28, or the blades and their supporting arms may be made integral or all 5 in one piece.

In this instance a lever, 29, as shown, is used with a handle, 30. This lever is connected to the shafts, 7 and 21, by means of the bearings, 31 and 32 respectively, and 10 may be moved to any position on the shafts as to accommodate itself to and not interfere with the adjustment of the shearing members, 22 and 23.

The distances between centers of the 15 shafts, 6—21 and 7—21, being the same, the arcs scribed by the extension arms, 10 and 11, are identical enabling the knife edges, 33 and 34, to constantly assume a horizontal position throughout the cutting stroke.

20 This is a very important feature as it is essential that the full length of the knife edges, 33 and 34, should touch and come in contact with the top of the cutting board, 35, and of the material being cut to insure 25 the cutting of the last sheet or thickness of paper lying next to the cutting board, and to prevent displacement of the sheets. The blades, 26 and 27, by means of the shafts; and swinging arms engage the paper and 30 move in the part of the arc which give them the necessary shearing motion so desired in all paper cutting machines.

The cutting board, 35, is secured to the frame members, 1 and 2. To assist in determining the width of the print or paper 35 to be cut the board may be scored as shown at 37 to any desired number of graduations. A gage and stop, shown at 38, and having a tongue, 39, inserted in an opening, 40, to 40 hold it in position may be used to fix and indicate the spacing of the blades, by having any number of these gages of various widths and keeping the inside surfaces of the blades in sliding contact with the sides, 45 41 and 42 of the gage when the blades are in operation, and prevent the blade members from creeping on the shafts and cutting or trimming either too little or to much of the margin of the photographic prints.

50 Another stop, 43, may be used in conjunction with the gage and stop, 38. This adjustable stop, 43, is held in place by the nut, 44, in the slot, 45, in the cutting board, 35. The machine may be permanently fastened 55 to a table or the like by means of screws or bolts being inserted in the holes, 46 in the end frame bars, 3, and 4.

In the operation of the machine the prints,

or sheets, are placed upon the cutting-board in multiple thicknesses with the edges in 60 contact with the abutment or stop, 43, and the gage, 38. As previously explained the blades, gages and stops are adjusted according to the graduations to determine the cut, the knives or blades, 27, are then made to 65 move down by pressure on the handle operating with a shearing motion to cut opposite edges of paper or prints, as shown in fine dotted lines in Fig. 3, and then moved back to normal position when the operation is complete for the trimming of the 70 two margins or borders. After the complete supply of prints have been trimmed or cut along the end edges the machine is then readjusted and the prints are trimmed along 75 their side edges.

Having thus described a paper or photographic print cutting machine, embodying my invention specifically in order that it may be made and used by those skilled in 80 the art, I would have it understood that I do not intend to limit my invention to the details thus described.

What I claim and desire to secure by Letters Patent is:

85 1. In a paper cutting machine, a frame, a cutting board thereon, four arms pivoted adjacent the horizontal plane of the cutting board, to swing above the cutting board, two cutting blades pivotally connected to said arms to swing toward and from the cutting board in parallel relation thereto, and an actuating lever connected to the swinging members, and projecting upward therefrom.

95 2. In a paper cutting machine, a frame, a cutting board thereon, arms pivoted adjacent the horizontal plane of the cutting board, to swing above the cutting board, two cutting blades pivotally connected to said arms to swing toward and from the cutting board in parallel relation thereto, and an actuating lever connected to the swinging members and projecting upward therefrom, the cutters being adjustable toward and 100 from each other in parallel relation, gages on the cutting board at right angles to each other, one of said gages being adjustable at right angles to the knives to determine the 105 margin to be cut.

110 Signed by me at Baltimore, Maryland, this 10th day of December, 1919.

VENE L. FIDLER.
